UNWINDING MEANS FOR THREADS, CORDS, AND THE LIKE

Alfred Edwin Herbert, Joseph Woods, and Richard Turner, Rochdale, England, assignors to John Bright & Brothers Limited, Rochdale, England

Application April 22, 1952, Serial No. 283,561

Claims priority, application Great Britain May 3, 1951

2 Claims. (Cl. 242—156)

This invention has reference to stretching frames for threads, cords and the like and has for its object to provide means whereby threads, cords and the like, hereinafter for convenience referred to as cords, when being stretched and wound on the bobbin shall be more evenly stretched throughout their length than is found to be possible by the present methods.

For certain purposes for which cord is used, it is necessary to stretch it so that fabrics into which it is woven shall be of a specified stretch, or at least shall not stretch so much as they would if the cord were used just as it is spun or twisted and not stretched. It will be understood that to this end it is necessary that the cord, and all of it, if possible, shall be evenly stretched or elongated, but stretching machines as used at present do not produce an even stretch or elongation, and this may apply more particularly to cords produced by ring twisting.

In machines of the kind to which this invention applies, the spun or twisted cord, on a bobbin, is mounted on the machine, and the cord, after passing round a pair of grooved rollers, with conical parts on them, which are the stretching rollers, is led to a bobbin above, mounted horizontally and rotated by contact with a driven roller on which it rests. In this way the end of the cord from the full, or let-off bobbin below is attached to the empty bobbin above so that as the top bobbin fills, the other empties and consequently the speeds and weight of the bobbins are varying throughout the operation, and the stretch also varies, but tests have shown that at the beginning of a run, the tension on the cord is much less than the tension at the end of the run, and consequently there is a higher elongation or greater stretch toward, and at, the end of the winding than at the beginning.

Some existing machines are provided with a swinging weight acting as a brake on the bottom bobbin but the construction and operation have not been successful in progressively regulating the tension of the cord being wound off. It was believed that a more even stretch could be obtained by controlling the rotational speeds of the bobbins and experiments were made to test this theory. To some extent it was found correct, more particularly with regard to the bottom bobbin, which it will be understood is an idler from which the cord is drawn, but it was not quite the same with the top bobbin, where it was believed, the increasing weight was a factor of difficulty in that, the frictional engagement of the top bobbin with its driving roller below must vary with the weight. Probably the changing diameters of the bobbins also has an effect on the tension and stretch.

Accordingly further tests and experiments were made which resulted in a construction which is the subject of this invention, and according to the invention, in a stretching frame for cords the stretch of the cord is made more even, by applying to the bottom or take-off bobbin a brake which applies a declining pressure as the

2

bobbin empties and applying to the top bobbin a weight which declines as the bobbin fills.

The invention is more particularly described with reference to the accompanying drawings in which:

5 Fig. 1 is a side view of the take-off bobbin bracket fitted with braking mechanism for the bobbin according to the invention.

Fig. 2 is an end view from the right of Fig. 1, and Fig. 3 is a diagrammatic view showing how rotation of

10 the top or take-up bobbin is controlled.

As shown in the drawings and referring first to Figs. 1 and 2, the bottom or take-off bobbin bracket 4 is mounted to the machine frame by bolts 5. The bobbin, whose position is shown by dotted lines in Fig. 1 is supported on an incline between the arms of bracket 4, and rotates 15 on a cone-bearing 6 at the lower end, and a spring-loaded plunger 7 at the other end, which arrangement affords the quick removal and mounting of bobbins.

Mounted on the limbs of the bracket 4 at the side are upstanding supports 8 and 9 respectively, and these are adjustable laterally for which purpose each is secured to the bracket by bolts 10, individual adjustment being effected by mounting washers 11 of the desired thickness on the bolts between the bracket and the supports themselves as shown in Fig. 2.

30 Pivoted at 12 and 13 to the supports 8 and 9 respectively are arms 14 which project from a weighted member 15 having a braking surface 16 which engages the surface of the bobbin or the surface of cord wound thereupon. Pivots 12 and 13 are not located in the vertical plane passing through the axis of the bobbin but are to one side of it, and the arms 14 are curved so that the weighted member 15 always swings inwardly to engage the bobbin, the pressure it exerts on the bobbin declining as the centre of gravity of the weighted member 15 swings more nearly to a vertical position under the pivots 12 and 13 which is of course as the bobbin 35 empties. The bobbin is not shown in Fig. 2 but the weighted member 15 is shown in the position it occupies when the bobbin is partially unwound.

40 When the bobbin is nearly empty, it is desirable to remove the braking pressure entirely and to this end the weighted member 15 is formed with a bifurcated tail 17 which moves astride a fixed peg 18 projecting from a web 19 on the bracket 4. On this peg is a compression spring 20 bearing against a washer 21 also on the peg, so that as the weighted member 15 swings gradually inward under its own weight the tail 17 moves astride the peg 18, engages the washer 21 and tends to compress the spring after it has moved inwardly for a predetermined distance. When the washer is first encountered by the tail of the weighted member, the spring is first compressed slightly, but as the pressure increases, the spring reaction likewise increases until the spring is fully compressed whereupon the weighted member is held against further movement and does not apply any braking effect to the rotary bobbin.

45 It will be appreciated that lateral adjustment of supports 8 and 9 is critical with respect to the amount of braking pressure applied throughout, since this is largely dependent on the positions of pivots 12 and 13, in relation to the bobbin axis.

50 Rotation of the top or take-up bobbin is controlled in a different manner, as here the speed is not the only factor to be directly governed.

55

It will be appreciated that lateral adjustment of supports 8 and 9 is critical with respect to the amount of braking pressure applied throughout, since this is largely dependent on the positions of pivots 12 and 13, in relation to the bobbin axis.

Rotation of the top or take-up bobbin is controlled in a different manner, as here the speed is not the only factor to be directly governed.

60 It has already been pointed out that as the weight of the top bobbin increases so does its frictional engagement with its driving roller below increase, and for this reason the control on the top bobbin is in the form of a weight control, illustrated diagrammatically in Fig. 3, which shows the positions of the bobbin and weighting means at two stages of the operation.

As shown in Fig. 3 there is pivoted at a point 22 behind the friction roller 23 a bell-crank lever 24 having weights 25 and 26 respectively at its ends. The lever 24 is so pivoted that, when the bobbin 27 is empty one arm is vertical and the other horizontal, the weight on the horizontal arm lying on the bobbin in front of a vertical plane through the bobbin axis. In Fig. 3 this position is shown by full lines.

As cord is wound on the bobbin, weight 25 is lifted by the cord as the diameter increases and the vertical arm is gradually tilted back to the chain-dotted position so that weight 26 begins to counteract weight 25 which rests on the cord. This movement continues until the moment of weight 26 exceeds the counter-moment of weight 25 whereupon weight 26 swings over and lifts weight 25 completely off the bobbin. Provision is made of course for the bobbin axis to rise along a line radial to the friction roller 23 as the cord builds up.

The weights 25 and 26 can be made adjustable or detachable so that the leverage can be adjusted to ensure that the latter weight is lifted clear at correct time, that is when the bobbin, including the cord wound on it, is itself heavy enough to provide the desired pressure between it and the driving roller; and the weight 25 may be in the form of a roller.

It is found that by using the adjustable brake on the bottom bobbin, and the adjustable weight on the top bobbin as described, a more even stretch can be imparted to the cord than has been hitherto obtained.

We claim:

1. In a stretching frame for cords, threads and the like, a U-shaped bracket for each take-off bobbin, and braking means applied to said bobbin, said braking means comprising a pivoted member normally engaging the bobbin under its own weight, a bifurcated projection on said pivoted member, a peg on said bobbin bracket astride of which peg said bifurcated projection moves, and a spring on said peg, said spring being compressed by said projection as the bobbin empties so as to counteract the gravitational pressure of said pivoted member on the bobbin, said spring becoming fully compressed before the bobbin empties so as to hold said pivoted member

out of contact with the bobbin, and relieve the braking pressure exerted thereon, during the final stage of unwinding.

2. For use with a let-off bobbin, a braking device comprising, in combination, supporting means including bearing means for supporting the let-off bobbin; weighted downwardly extending lever means pivotally supported on said supporting means at a pivoting point located above said bearing means, said weighted lever means having a portion adapted to be supported by and thereby frictionally engage the let-off bobbin for braking the same, and being adapted to turn from a first higher braking position to a second lower braking position for reducing the braking pressure on the let-off bobbin as a diameter of the let-off bobbin is reduced due to winding off of thread; and stop means engaging and holding said weighted lever means in said second braking position whereby the let-off bobbin is relieved from braking pressure when the diameter thereof further decreases due to winding off of thread.
